(57) **CLAIM**

The ornamental design for an X-ray irradiation apparatus, as shown and described.

DESCRIPTION

FIG. 1 is a top, front and left side perspective view of an X-ray irradiation apparatus showing my new design;

FIG. 2 is a top, rear and right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a top, front and left side perspective view thereof in a state that a guard part is removed from the state shown in FIG. 1;

FIG. 10 is a top, rear and right side perspective view thereof in a state that the guard part is removed from the state shown in FIG. 2;

FIG. 11 is a top plan view thereof in a state that the guard part is removed from the state shown in FIG. 5;

FIG. 12 is a bottom plan view thereof in a state that the guard part is removed from the state shown in FIG. 6;

FIG. 13 is a left side elevational view thereof in a state that the guard part is removed from the state shown in FIG. 7;

FIG. 14 is a right side elevational view thereof in a state that the guard part is removed from the state shown in FIG. 8;

FIG. 15 is a top, front and left side perspective view of an X-ray irradiation apparatus showing a second embodiment of my new design;

FIG. 16 is a top, rear and right side perspective view thereof;

FIG. 17 is a front elevational view thereof;

FIG. 18 is a rear elevational view thereof;

FIG. 19 is a top plan view thereof;

FIG. 20 is a bottom plan view thereof;

FIG. 21 is a left side elevational view thereof;

FIG. 22 is a right side elevational view thereof;

FIG. 23 is a top, front and left side perspective view thereof in a state that a guard part is removed from the state shown in FIG. 15;

FIG. 24 is a top, rear and right side perspective view thereof in a state that the guard part is removed from the state shown in FIG. 16;

FIG. 25 is a top plan view thereof in a state that the guard part is removed from the state shown in FIG. 19;

FIG. 26 is a bottom plan view thereof in a state that the guard part is removed from the state shown in FIG. 20;

FIG. 27 is a left side elevational view thereof in a state that the guard part is removed from the state shown in FIG. 21; and,

(Continued)

FIG. 28 is a right side elevational view thereof in a state that the guard part is removed from the state shown in FIG. 22. The broken lines showing the portions of the X-ray irradiation apparatus in all views shown represent unclaimed subject matter and form no part of the claimed design.
